Primary Examiner — Manpreet S Matharu*Assistant Examiner* — Keith J Wilson(74) *Attorney, Agent, or Firm* — Jonathan E. Grant; Grant Patent Services(57) **CLAIM**

I claim the ornamental design for a toy track segment, as shown and described.

DESCRIPTION

FIG. 1—is a perspective view of the toy track segment;
FIG. 2—is an overhead view thereof;
FIG. 3—is a bottom view thereof;
FIG. 4—is a front view thereof;,
FIG. 5—is a back view thereof;
FIG. 6—is a first side view thereof;
FIG. 7 is a second side view thereof; and,
FIG. 8 is a perspective view showing the toy track segment. The broken lines used in FIG. 3 represents portions of a toy track segment. The broken lines shown in FIG. 8 represents environment only. All broken lines used form no part of the claimed design.

1 Claim, 6 Drawing Sheets(56)
